CLAIM

The ornamental design for a compact disk storage rack, as shown and described.

DESCRIPTION

FIG. 1 is a front, top and left side perspective view of a compact disk storage rack embodying my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, left side and top perspective view of another embodiment of a compact disk storage rack embodying my design, illustrating additional storage compartments, the right side is a mirror image of the left side shown, and the undisclosed top, bottom, and rear views have the same appearance as the first embodiment in a taller form.
